UNITED STATES PATENT OFFICE.

PAUL H. DARRAH, OF GOODYEARS BAR, CALIFORNIA.

ORE-CONCENTRATOR.

1,101,415.

Specification of Letters Patent. Patented June 23, 1914.

Application filed October 28, 1913. Serial No. 797,763.

To all whom it may concern:

Be it known that I, PAUL H. DARRAH, a citizen of the United States, and a resident of Goodyears Bar, in the county of Sierra and State of California, have invented a new and Improved Ore-Concentrator, of which the following is a full, clear, and exact description.

This invention relates to ore concentrators and has particular reference to means for acting mechanically for the separation of dry ores.

Among the objects, therefore, of the invention is to provide a machine having various adjustments or capabilities of action so as to meet the demands of various types or conditions of ores to be treated.

The foregoing and other objects of the invention will hereinafter be more fully described and claimed and illustrated in the drawings forming a part of this specification in which like characters of reference indicate corresponding parts in all the views, and in which—

Figure 1 is a plan view of a preferred embodiment of the invention; Fig. 2 is a side elevation of the same; Fig. 3 is an upper end elevation; Fig. 4 is a longitudinal section substantially horizontal on the line 4—4 of Fig. 2, showing the hammer mechanism in plan; Fig. 5 is a view similar to Fig. 4 but taken on the line 5—5 of Fig. 2; Fig. 6 is a vertical longitudinal section on the line 6—6 of Fig. 5; Fig. 7 is a vertical transverse section on the line 7—7 of Fig. 4; Figs. 8 and 9 are transverse sectional details on the lines 8—8 and 9—9 respectively of Fig. 1, indicating the changing cross section between the upper and lower ends of the ore directing slats; Fig. 10 is a detail of the spring connection on the line 10—10 of Fig. 3; Fig. 11 is a detail of the connection with one of the hammer levers; Fig. 12 is a detailed view of one of the hammers; Fig. 13 is a detail of the means for securing the limit bars controlling the action of the hammers, the view being taken on the line 13—13 of Fig. 7; Fig. 14 is a detailed view showing the means for preventing the table from sagging downwardly toward the discharge end of the machine; and Fig. 15 is a detailed view of the connections between the hammer mechanism and the means for vibrating the table laterally.

The several parts of the device may be made of any suitable materials, and the

relative sizes and proportions, as well as the general design of the mechanism, may be varied to a considerable extent without departing from the spirit of the invention hereinafter more fully set forth and specifically claimed.

This invention comprises a frame 16 comprising longitudinally inclined bars 17, 18 and 19 and end supporting legs 20 and 21, said parts being arranged in duplicate. On the front or discharge side of the machine I also provide a pair of braces 22 so as to strengthen the machine so as to better resist the shocks due to the lateral vibrations of the machine.

Arranged at the head and foot of the machine are pairs of uprights or standards 23, preferably two at each end, and at the upper end of each of these standards is an angle bracket 24 having an arm 25 extending toward the opposite end of the machine. An eye bolt 26 is adjustably connected by means of a nut 27 to said arm 25 and supports a hanger 28 for the adjacent corner of the table 29. These hangers serve not only as means for suspending the table 29 so as to permit lateral movements to be imparted thereto, but through the nuts 27 and eye bolts 26 the relative elevations of the ends of the table may be varied in accordance with the various kinds of ore or matter to be treated. The table furthermore is prevented from sagging or shifting endwise due to the discharge thereupon of material by means of a pair of links 30 connected to a cross piece 31 at the upper end of the table and having loose or pivotal connection at their upper ends to a cross rod 32 supported upon a pair of brackets 33 extending outwardly from the head end of the machine.

As shown in Figs. 1, 3 and 9, the table comprises essentially a floor 34 constructed of tongue and groove material connected substantially tight and arranged longitudinally along the upper surface thereof are tapered slats 35. Said slats are each constructed to provide a vertical rear face 35' and a beveled front face 35''. The taper of these slats is such that a wide space for receiving and conveying materials is provided adjacent the upper end of the machine and a comparatively narrow or V-shaped space is provided at the lower end. The material to be treated is deposited upon the upper rear corner of the table or the upper right hand corner as viewed in Fig. 1, and during the

vibration of the table, as described farther below, such material is caused to be moved forwardly and toward the left, the larger and lighter particles being caused to pass from one space between the slats to another until they are delivered over the front edge of the table or at the bottom of Fig. 1, while the smaller and heavier particles are conducted along the grooves between slats and finally discharged therefrom at the extreme lower end of the table. At the rear edge of the table a flange 36 is provided to prevent the accidental discharge of the material thereover. At 37 I show a diagonal cleat so arranged across the lower end of the table as to cause any large or light particles which project above the grooves between the slats to be delivered positively over the front edge of the table.

In order to agitate the material carried by the table and to facilitate the separation or concentration thereof, I provide means for acting upon the table both to tap it from beneath and to cause it to swing laterally resulting in the bumping thereof. For the purpose of tapping the bottom of the table I provide a plurality of hammers 38. These hammers are arranged in sets, shown as four in a set, and each set mounted upon a rock shaft 39 journaled in bearings 40 at its ends connected to the side rails 17 of the frame. Said hammers of each set are arranged in substantially the same plane and are caused to strike or tap upwardly against the bottom of the table simultaneously by means of a lever 41 connected to the rock shaft 39 to which the hangers are connected. Each hammer includes a spring arm 42 shown particularly in Fig. 12 as being secured at the desired circumferential adjustment to the rock shaft 39 by means of a set screw. A limit bar 43 extends across the machine and is connected by means of a pair of clips 44 to the upwardly extending portions 17' of the side rails. Said clips are provided with slotted feet 44' as shown in Fig. 13 so as to vary the position of the limit bar 43 with respect to the hammers. In other words, the bar 43 is preferably so arranged as to hold the hammers normally out of engagement with the bottom of the table so as not to interfere with the lateral vibrations thereof. The hammers, therefore, on striking said bar under force will put the spring arms under tension and the hammers will therefore strike the bottom of the table but will rebound therefrom due to the position of the bar 43. As a convenient means for causing the tapping action of the hammers I provide a rod 45 connected at one end by adjustment nuts 46 to the lever 41, the other end of the bar being connected to and acted upon by a spring 47 secured by an eye bolt 48 to a cross piece 49 at the upper end of the machine. Said eye bolt 48 is of consider-

able length so as to give a wide latitude of adjustment for the spring.

The foregoing description of the hammer mechanism will be understood as being applicable to a plurality of sets of hammers, shown as six in number, extending throughout the length of the machine.

At 50 I show a power shaft journaled transversely and substantially midway between the ends of the machine in bearings 51 on the bars 19. On this power shaft are arranged tight and idle pulleys 52 through which the driving rotation of the power shaft 50 is controlled from any suitably arranged motor (not shown). I also show a plurality of counter shafts 53 arranged parallel to the power shaft 50 and similarly journaled upon the beams 19, the location of the shafts being preferably substantially below the respective rock shafts 39. On each of the shafts just described I mount a cam 54. These cams are so arranged and secured to the shafts as to act in succession upon the several downwardly depending levers 41, the countershafts being driven simultaneously and preferably at the same speed with the power shaft 50 by any suitable form of belt or chain gearing indicated at 55. Any cam, therefore, when rotated, as indicated in Fig. 6, coming into engagement with the lower end of a lever 41 will put the corresponding spring 47 under tension, and as soon as the point of the cam passes the end of the lever the power of the spring will be exerted to cause the set of hammers pertaining to such lever to strike the bottom of the table, as above described. The rearward movement of the lever under the force of the spring is limited or controlled by a limit bar 43' adjustably secured to the rails 18 by clips 44' corresponding to those above described. The successive and continual tapping action of the hammers along the bottom of the table will cause the desired concentrating action on the material.

The lateral vibratory movement of the table is effected as follows: At 56 is arranged a shaft parallel to the longitudinal axis of the machine and journaled upon a pair of cross pieces 57 shown and supported upon the beams 17. Said shaft 56 is driven from the power shaft 50 through a vertical shaft 58 and suitable beveled gearing, and connected to said shaft 56 is a cam 59 adapted to strike or act upon an angle bracket 60 adjustably secured through a slot 60' to the bottom of the table, as shown best in Fig. 7. The extent to which the table is oscillated laterally by the action of the cam 59 will depend upon the position at which the bracket 60 is adjusted. The cam 59 preferably has a single point while the cams 54 are double; hence, assuming that the gearing between the power shaft 50 and the shaft 56 is all substantially of the same size,

the table will be given one lateral swing to each two taps of all the hammers. The lateral movement of the table, due to the direct action of the cam, is comparatively gradual or without shock, and such movement causes a spring 61 to be put under tension. Said spring is connected to an adjustable rod 62 secured to the front rail 17' and the force of the spring causes the return of the table more or less violently, causing it to impinge against one or more stops 63 adjacent the main frame. This action is such as to cause the larger and lighter particles of the mass to be pitched or thrown forwardly 15 toward the front edge of the table simultaneously with the conveyance or direction of the entire mass downwardly toward the lower end of the table by means of the slats.

Having thus described my invention, I claim as new and desire to secure by Letters Patent:

1. In an ore concentrator, the combination of a frame, a table suspended above the frame, a plurality of hammers journaled upon the frame below the table, lever and cam mechanism to move said hammers in one direction, a series of springs serving to

cause the hammers to move quickly in the opposite direction to tap against the bottom 30 of the table, and a series of cross bars between the hammers and the bottom of the table to keep the hammers out of normal contact with the table.

2. In an ore concentrator, the combination 35 of a frame, a table supported above the frame and adapted to move laterally with respect thereto, a series of rock shafts journaled transversely of the frame beneath the table, a series of hammers connected to each 40 rock shaft, lever and cam mechanism to cause the rock shafts to carry the hammers away from the table, additional means to cause the hammers to be projected toward the table, each of the hammers including a 45 spring arm, and means between the hammer arms and the table to cause the hammers to be held normally out of contact with the table.

In testimony whereof I have signed my 50 name to this specification in the presence of two subscribing witnesses.

PAUL H. DARAH.
